UNITED STATES PATENT OFFICE

PHILIP GOLDSSTONE, OF WOODHAVEN, NEW YORK, ASSIGNOR TO GIBBS & HILL, OF NEW YORK, N. Y., A PARTNERSHIP OF NEW YORK

APPARATUS FOR REDUCING INTERFERENCE

Application filed July 30, 1927. Serial No. 209,445.

This invention relates to electric power transmission or distributing systems. More specifically it relates to alternating current transmission or distributing systems and has for one of its principal objects to provide a method and means for reducing the undesired inductive interference effect of such systems.

Certain of the objects of the invention are to provide improvements for certain classes of services and under certain conditions of operation in the inventions disclosed and claimed in an application filed by me on September 10, 1921, and which is now United States Patent No. 1,564,845, patented December 8, 1925. These and other objects and advantages will appear as the invention is hereinafter disclosed.

Referring to the drawings which illustrate what I now consider preferred forms which the present invention may assume:

Fig. 1 is a diagram illustrating the invention applied to a single section of a one track, single phase electric railway system.

Fig. 2 is a diagram for facilitating more detailed disclosure of the invention.

Figs. 3, 4, 5, 6 and 8 are views generally similar to Fig. 1 but illustrating different forms of the invention.

Fig. 7 is a diagrammatic cross-section taken on the line 7—7 of Fig. 6.

While the invention may be applied to multi-track, or multi-phase, or other systems, I have in order to avoid surplusage in illustration and description, shown it applied to a single section of a one track, single phase electric railway system. Referring first to Fig. 1 it will be seen that I have shown the usual high tension transmission or feeder conductors 10, 10' supplied with alternating current, at any desired voltage or frequency, through a step-up transformer 11. Step-down transformers located at spaced substations or transformer stations are adapted to supply alternating propulsion current at a lower voltage to the contact conductor, shown as a trolley wire 12, and to the return conductor 13, shown as a track or ground return, of the railway. The primary windings 14, 16 are shown connected across the

line 10, 10', the secondary windings 15, 17 being connected across the lines 12, 13. Each of the step-down transformers is provided with a secondary winding 15', 17', each connected at one end or terminal to the grounded end of its adjacent secondary winding 15, 17. As thus far described the arrangement shown in Fig. 1 is generally the same as that shown in Fig. 1 of the above mentioned patent. However, the extra conductor 19 shown in the patent is dispensed with and one or more of the high tension transmission conductors made to serve its purpose. While the desired object may be obtained under certain conditions by connecting the ends of windings 15' and 17' to intermediate points of the primary windings of the transformers 14, 16, I have shown, in Fig. 1, connections made to the ends of the said primaries or directly to one of the high tension conductors 10'.

A balancing circuit is formed by the conductor 10', coil 15', conductor 13, and coil 17' to perform the same or substantially the same function in reducing inductive interference as is performed by the conductor 19, coil 15', conductor 13, and coil 17' in the arrangement disclosed in the patent. It will be noted in the present arrangement that the conductor 10' serves in a dual capacity, i. e. as one of the conductors of the balancing circuit and also as one of the conductors of the high tension transmission line. This effects greater economy since the conductor 19 (shown in the patent) is not only dispensed with but also the breaker or protective equipment or appurtenances usually required for such a conductor.

In the use of a system such as that shown in Fig. 1 of the patent it is sometimes desirable to increase the voltage of the conductor 19 to a high value, but when this is done the balancing effect of the conductor 19 in compensating for the static effect of the conductor 12 is not only more or less lost but if and when the voltage of the conductor 19 is made too great, it may have a detrimental effect by producing static induction in adjacent communication conductors. In the arrangement illustrated in present Fig. 1 the

static effect of the balancing conductor 10' is balanced by the static effect of the other high tension conductor 10, these two conductors 10 and 10' being at equal but opposite potential. These two supply conductors 10 and 10' may conveniently be maintained at equal but opposite potential by grounding the mid-point of the secondary of the transformer 11 as is common practice in the art.

10 While it is believed that the foregoing disclosure will enable those skilled in the art to make and use the now preferred form of the present invention, I shall describe it in further detail and then refer to some of the 15 various modified forms which the invention may assume.

The desired condition to be attained with the balanced system is that no current or substantially no current shall flow in the trolley-rail circuit 12-13 when the load is concentrated at one and then the other substation (1 and 2 in Fig. 1). When this condition is met, a load 18 or loads intermediate 1 and 2 will produce substantially no net induction 25 in a length of circuit between stations 1 and 2 under normal conditions for which the present invention is intended.

The system shown in Fig. 1 is analytically represented in Fig. 2, in which: T represents the transmission circuit 10-10' having impedance Z_t between stations 1 and 2; TR represents the trolley rail circuit 12-13 having impedance Z_{tr} between stations 1 and 2; TF represents the balancing circuit having impedance Z_{tf} ; Z_1 , Z_2 , and Z_6 are the equivalent impedances of the transformer 14; Z_4 , Z_5 and Z_3 are the equivalent impedances of the transformer 16; M_1 is the mutual impedance between the circuits TR and TF; and 40 M_2 is the mutual impedance between the circuits T and TF; all impedances being represented on a trolley rail voltage basis. It will be borne in mind that the balancing circuit TF (15'-10'-17'-13) does not comprise 45 inter-station conductors other than those which serve also as conductors in the transmission and trolley rail circuits.

The values of Z_1 , Z_2 and Z_6 with respect to 50 the transformer are shown by the following equations:

$$(1) \quad 2Z_1 = Z_a + Z_b - Z_c$$

$$(2) \quad 2Z_2 = Z_c + Z_a - Z_b$$

$$(3) \quad 2Z_6 = Z_c + Z_b - Z_a$$

55 in which: Z_a is the impedance of the transformer when passing current from the coil 14 to the coil 15 with the coil 15' open; Z_b is the impedance of the transformer when 60 passing current from the coil 14 to the coil 15' with the coil 15 open; and Z_c is the impedance of the transformer when passing current from the combination of coils 15 and 15' in series, to the coil 15 with the coil 14 open.

65 The values of Z_4 , Z_5 , and Z_3 with respect to

the transformer 16, 17, 17' may similarly be derived.

Assuming a unit ampere load at station 2 and no current in the circuit TR, the current divisions are shown by the arrows in Fig. 2. For the condition of no current in the circuit TR, the voltage drop from point 3 to point 2 by the path 3-4-2, must be equal to the voltage drop from the point 3 to the point 2 by the path 3-1-2, and the following relationship exists:

$$(4) \quad i_1(Z_3 + Z_{tf} + Z_6) + (1 - i_1)M_2 + Z_5 = i_1M_1$$

or

$$(5) \quad Z_3 + Z_{tf} + Z_6 = M_1 + M_2 - \frac{M_2 + Z_5}{i_1} \quad 70$$

i_1 may be found from the following equation:

$$(6) \quad i_1(Z_1 + Z_3 + Z_{tf} + Z_6) + (1 - i_1)M_2 = \frac{(1 - i_1)(Z_t + Z_4) + i_1M_2}{85}$$

or

$$(7) \quad i_1 = \frac{Z_t + Z_4 - M_2}{Z_1 + Z_3 + Z_{tf} + Z_6 + Z_t + Z_4 - 2M_2} \quad 90$$

Since Z_3 , Z_5 , or Z_6 may be designed to be either positive or negative, Equation (5) is a possible condition.

For a unit ampere load at station 1 and no current in the circuit TR the condition to be satisfied is:

$$(8) \quad Z_2 + i_1'(Z_3 + Z_{tf} + Z_6) - i_1'M_2 = i_1'M_1$$

or

$$(9) \quad Z_3 + Z_{tf} + Z_6 = M_1 + M_2 - \frac{Z_2}{i_1'} \quad 100$$

i_1' may be obtained from the following equation:

$$(10) \quad (1 - i_1')Z_1 = i_1'(Z_t + Z_4 + Z_3 + Z_{tf} + Z_6) - 2i_1'M_2 \quad 105$$

or

$$(11) \quad i_1' = Z_1 / (Z_1 + Z_3 + Z_{tf} + Z_6 + Z_t + Z_4 - 2M_2)$$

In order that (5) and (9) may be satisfied:

$$(12) \quad M_1 + M_2(1 - 1/i_1) - Z_5/i_1' = M_1 + M_2 - Z_2/i_1'$$

from which:

$$(13) \quad (Z_5 + M_2)/i_1 = Z_2/i_1' \quad 115$$

Substituting the values of i_1 and i_1' :

$$(14) \quad \frac{Z_5 + M_2}{Z_1 + Z_4 - M_2} = \frac{Z_2}{Z_1}$$

$$(15) \quad Z_5 = \frac{Z_2}{Z_1}(Z_t + Z_4 - M_2) - M_2 \quad 120$$

$$(16) \quad Z_4 = \frac{Z_1}{Z_2}(Z_5 + M_2) + M_2 - Z_t$$

Substituting (15) and (7) in Equation (5):

$$(17) \quad Z_3 + Z_{tf} + Z_6 = \frac{Z_1(M_1 + M_2) - Z_2(Z_1 + Z_t + Z_4 - 2M_2)}{Z_1 + Z_2} \quad 125$$

which is the condition to be met.

In the form of invention shown in Fig. 3 the elements 110, 111, 112, 113, 114, 115, 115', 116, 117, and 117' correspond generally to the elements 10, 11, 12, 13, 14, 15, 15', 16, 17, and 17', respectively of Fig. 1. It will be noted, however, that additional windings 115'' and 117'' are provided corresponding generally to windings 115' and 117', the connections being as shown. In this case both high tension transmission wires 110, 110 serve not only in that capacity or rôle but also as conductors of two balancing circuits. The one balancing circuit may be traced as follows: 115'—110 (lower)—117'—113; and the other balancing circuit as follows: 115''—110 (upper)—117''—112. This system may also be made to function by omitting the coils 14 and 16, as shown in Fig. 4. In this case the coils 115''—115—115' and 117''—117—117' act as auto-transformers across the high tension transmission line 110—110.

It will be understood that in the arrangements of Figs. 3 and 4, as in the case of Fig. 1, the design is such that when the load is concentrated at station 1 there is no current or substantially no current in the trolley rail circuit, and when the load is concentrated at station 2 there is no current or substantially no current in the trolley rail circuit.

In Fig. 5 I have illustrated a somewhat different form of apparatus and connections operating in a somewhat different way to reduce inductive interference. The elements 210, 210, 211, 212, 213, 214, 215, 216 and 217 will be recognized in view of generally similar elements shown in the preceding figures and require no further description. In addition there are provided transformer-coupled auxiliary conductors 212' and 213'. The conductor 212' is connected to and extends between the trolley buses or trolley terminals of the secondaries 215 and 217. The conductor 213' is connected to and extends between the ground or track terminals of the same secondary coils 215, 217. These two conductors 212' and 213' are coupled by means of a transformer whose primary 40 is in the conductor 212' and whose secondary is in the conductor 213'. Any difference in potential between the secondaries 215 and 217 will cause a current (say I') to flow in the trolley conductor 212 and a current (say I'') to flow in the conductor 212'. The current I' in conductor 212' is so stepped up by the transformer 40—41 that the current flowing in the secondary coil 41, and consequently in the conductor 213', is equal in magnitude to the sum of the currents in the conductors 212 and 212', i. e. I' plus I'' . This current in the conductor 213' (i. e. I' plus I'') completes its circuit through the track 213 but in an opposite direction to the current (I' plus I'') tending to flow in the track circuit as a return path for the conductors 212 and 212'. The net effect is that substantially no

current flows in the tracks due to unbalance of potential of the coils 215 and 217. The traction currents from an inter-station load return through the track to the adjacent substations 1, 2, in opposite directions and as the ampere-miles between one substation and the load are equal to the ampere-miles between the other substation and the load, the effect of the traction currents on adjacent communication circuits extending between stations is cancelled out.

The design of the conductors 212', 213' and their coupling transformer 40—41 is such that the current in the conductor 213' is substantially equal in value and in phase to the unbalanced currents in the conductors 212 and 212'.

I wish to emphasize that while my invention has other important advantages, it is primarily designed to reduce undesired interference between power systems and adjacent systems which occupy the same or adjacent or more or less remote rights of way. To simplify illustration I have omitted, from each of Figs. 1, 3, 4 and 5, illustration of the conductors of such adjacent systems but it will be understood that they are present in conditions of actual practice, as shown for example as a telephone wire in Figs. 6 and 8 to which I shall now refer.

In Figs. 6 and 7 I have illustrated a form of my invention in which undesired inductive interference is reduced and substantially eliminated in a manner specifically different from that employed in any of the forms of invention shown in Figs. 1, 3, 4 and 5. Referring to Figs. 6 and 7, it will be seen that the elements 310, 310, 311, 312, 313, 314, 315, 316 and 317, correspond respectively to the elements 10, 10', 11, 12, 13, 14, 15, 16 and 17, shown in Fig. 1; i. e. the system is shown as a single phase, single track, railway system. To facilitate explanation of the construction and operation of this (Figs. 6 and 7) form of the invention, it may be pointed out that the reason for most of the induction caused by a single phase electrification system upon another juxtaposed system, such as a telephone conductor C, is that the induction due to the contact conductor or trolley wire 312 is not equalized by the induction due to the return currents. The track 313 used as a return is, in practice, poorly insulated from the earth or ground G with the result that an appreciable percentage of current leaks off into the ground and returns by a path in the ground which is at a great distance from the telephone wire C as compared to the distance between the trolley wire and the telephone conductor C. In such case the induction from the trolley wire 312 upon the telephone conductor C is not neutralized by the induction from the track and ground return currents. In this form of my invention (Figs. 6 and 7), instead of employing the

specific construction and design shown in Figs. 1, 3, 4 and/or 5, and described hereinbefore. I so position a conductor B with respect to the telephone conductor C and so supply this conductor B with current that, having regard to the currents in the conductors (including the ground G) of the railway system and the distances from the telephone conductor C of the paths of the last mentioned currents, any otherwise unbalanced inductance upon the telephone conductor C is balanced out and substantially neutralized by the inductive effect of the said conductor B.

In Fig. 6 the conductor B is shown supplied with E. M. F. by a secondary winding 315' of the transformer 314—315 and a secondary winding 317' of the transformer 316—317, connected as shown. The number of turns and impedance of the windings 315' and 317' are such as to give the desired value of current through the wire B to effect neutralization, or substantially neutralize the inductive effect upon the telephone conductor C which would be present if the conductor B (or some means as shown in Figs. 1, 3, 4 and/or 5, and described in connection therewith) were not provided.

The form of invention shown in Figs. 6 and 7 will give very satisfactory results in reducing inductive interference of the railway system upon the telephone conductor when the design is such as to cause the following equation to be satisfied:—

$$I_5 = \frac{\text{Log}_{10} \left(\frac{L_1}{L_1'} \right)^{I_1} \frac{L_2}{L_2'} I_2}{\text{Log}_{10} L_5}$$

in which: I_1 is the current in each feeder wire 310, 310'; I_2 is the current in the trolley or contact conductor 312; I_3 is the current in the track 313; I_4 the current in the earth or ground G; I_5 the current in the neutralizing or balancing wire B; and L_1 , L_1' , L_2 , L_2' , L_3 , L_4 and L_5 , are the distances between the telephone conductor C and the other conductors as indicated in Fig. 7.

In Fig. 8 I have illustrated a form of invention in which no extended detailed description is needed in view of the description of preceding figures, notably Figs. 5, 6 and 7. The transformer 411, transmission conductors 410, 410', step-down transformers 414—415, 416—417, the trolley conductor 412, track 413, conductors B and W coupled by a transformer 440—441, and the telephone conductor C, will at one be recognized. In view of the foregoing disclosures and explanations, it will be apparent that by proper design the form of invention shown in Fig. 8 may be caused to function and operate in essentially the same manner as that shown in Figs. 6 and 7. The system shown in Fig. 8 may also be designed to embody some of the characteristics of operation of that shown in

Fig. 5 and some of that shown in Figs. 6 and 7.

In accordance with the requirements of the patent statutes I have disclosed now preferred forms of my invention. It will be understood that the specific physical embodiments herein disclosed are illustrated only diagrammatically and, to avoid confusion and surplusage, more or less auxiliary apparatus such as circuit breakers switches etc., which may prove desirable in practice, have been omitted. However, with the present disclosure before him, a man skilled in the art to which the invention pertains could make and practice the invention. It is to be borne in mind also that while it is at present preferred to employ the various features and elements in the combinations described, some of these may be altered and others omitted, and some of the features of each modification may be embodied in the others, without interfering with the more general results and effects outlined, and the invention extends to such use within the scope of the appended claims.

What I claim is:

1. An electrical system comprising in combination, a supply circuit, a distribution circuit including a plurality of working conductors, a plurality of transformers remotely located with respect to each other and having their primary windings connected to said supply circuit and having points of their secondary windings connected to said supply circuit and working conductors, the windings of said transformers being so related to said conductors and to each other as to reduce the external inductive effect of the said distribution circuit to a negligible value.

2. An electrical railway system comprising a supply circuit, a distribution circuit including a trolley conductor and a track conductor; and a plurality of spaced transformers, each having its primary connected across said supply circuit, each having a secondary winding connected across said trolley and track conductors, and each having a secondary winding connected across one of said distribution conductors and one of the conductors of the supply circuit; the impedances of the windings of said transformers being so proportioned relative to the impedances of said conductors and to each other that under average operating conditions the external inductive interference effect of said distribution circuit is substantially negligible.

3. An electrical railway system comprising a supply circuit, a distribution circuit including a trolley conductor and a track conductor; and a plurality of spaced transformers, each having its primary connected across said supply circuit, each having a secondary winding connected across said trolley and track conductors, each having a secondary winding connected across said trolley conductor and

- one of the conductors of the supply circuit, and each having a seconding winding connected across the track conductor and another of the conductors of the supply circuit; the impedances of the windings of said transformers being so proportioned relative to the impedances of said conductors and to each other that under average operating conditions the external inductive interference effect of said distribution circuit is substantially negligible. 10
4. An electrical railway system comprising a supply circuit, a distribution circuit including a trolley conductor and a track conductor; and a plurality of spaced auto transformers each having its primary connected across said supply circuit, each having a secondary winding connected across said trolley and track conductors, each having a secondary winding connected across said trolley conductor and one of the conductors of the supply circuit, and each having a secondary winding connected across the track conductor and another of the conductors of the supply circuit; the impedances of the windings of said transformers being so proportioned relative to the impedances of said conductors and to each other that under average operating conditions the external inductive interference effect of said distribution circuit is substantially negligible. 20
5. A system, for reducing undesired interference between an A. C. railway system and juxtaposed conductors, comprising in combination, high tension supply conductors extending along the route, lower tension contact and track conductors which receive propulsion energy from said supply conductors, spaced transformer windings connected in multiple with each other across said contact and return conductors, and means including one of said supply conductors for substantially eliminating unbalanced track return currents. 30
6. A system, for reducing undesired interference between an A. C. railway system and juxtaposed conductors, comprising in combination, high tension supply conductors extending along the route, lower tension contact and track conductors which receive propulsion energy from said supply conductors, spaced transformer windings connected in multiple with each other across said contact and track conductors, and means including one of said supply conductors and transformer windings in addition to said first named transformer windings for substantially eliminating unbalanced track return currents. 40
7. A system, for reducing undesired interference between an A. C. railway system and juxtaposed conductors, comprising in combination, high tension supply conductors extending along the route, lower tension contact and track conductors which receive pro-
- pulsion energy from said supply conductors, spaced transformer windings connected in multiple with each other across said contact and track conductors, and means including one of said supply conductors and transformer windings in addition to said first named transformer windings for substantially eliminating unbalanced track return currents without substantially changing the static effect of the supply conductors. 70
8. An electrical system comprising in combination a supply circuit, a distribution circuit including a plurality of working conductors one of which is a track conductor, a plurality of transformers remotely located with respect to each other and having their primary windings connected to said supply circuit and their secondary windings connected to said working conductors, the point in each secondary winding which is connected to the track conductor being connected to an intermediate point in the primary winding associated with that secondary winding, the windings of said transformers being so related to said conductors and to each other as to reduce the external inductive effect of said distribution circuit to a negligible value. 80
